UNITED STATES PATENT OFFICE.

FREDERICK A. PRESTON, OF HIGHLAND PARK, ILLINOIS, ASSIGNOR TO P. & M. COMPANY, OF CHICAGO, ILLINOIS, A CORPORATION OF ILLINOIS.

ANTICREEPER.

1,268,996.

Specification of Letters Patent. Patented June 11, 1918.

Application filed April 13, 1917. Serial No. 161,726.

To all whom it may concern:

Be it known that I, FREDERICK A. PRESTON, a citizen of the United States, residing at Highland Park, in the county of Lake 5 and State of Illinois, have invented a certain new and useful Improvement in Anticreepers, of which the following is a full, clear, concise, and exact description.

This invention relates to improvements in 10 one-piece rail anchors or anticreepers.

The objects of the invention are as follows: to provide an anchor of this type which is extremely effective and simple in construction and operation, and which may 15 be economically manufactured; to provide a rail anchor which may be readily and quickly applied to the base of a rail and which maintains a firm frictional engagement therewith under all conditions of service; and to provide a rail anchor which resists creeping in both directions, and which 20 can be reapplied successfully.

Other objects and advantages will become apparent from the following description, taken in connection with the accompanying drawings, wherein I have shown the preferred embodiment of my invention. It will be readily understood that the construction therein shown is for purposes of 25 illustration only and not as defining the limits of the invention, except as pointed out in the appended claims.

Figure 1 is a rear elevation of one form of the invention;

35 Fig. 2 is a top plan view thereof; and Figs. 3 and 4 illustrate another form of the invention.

The rail anchor is preferably formed of a single piece of high tension spring steel 40 arranged to grip the base of the rail 1, said rail being supported on the usual cross tie 2. In the drawings, the device is shown as provided with a substantially U-shaped projection 10, which co-operates with the 45 rail to exert horizontal tension on the sides of the base thereof in a manner as herein-after set forth, said U-shaped portion also serving as a tie abutment for the anchor to transmit the creeping thrust of the rail 50 directly to the cross tie 2. On either side of said U-shaped projection 10 and preferably in the same horizontal plane, substantially flat arms 11 and 12 are provided, said arms being adapted for engagement with

the under surface of the rail base, the ends 55 of said arms being bent upwardly and inwardly to form jaws 13 and 14 adapted to embrace opposite sides of said rail base to hold the anchor in firm frictional engagement therewith substantially as shown in 60 Fig. 1. These oppositely positioned jaws are held in firm engagement with the opposite sides of the rail base, by virtue of the lateral or horizontal tension exerted by the walls of the U-shaped projection 10 when 65 the anchor is sprung on to the rail.

The tie-abutting U-shaped projection 10 is preferably positioned to one side of the longitudinal axis of the rail. In the drawings it is shown positioned substantially beneath the inner end of the jaw 14, it being so positioned in order that the majority of the creeping thrust of the rail may be resisted by the jaw 14, in view of the powerful gripping action exerted on the rail base 75 thereby.

The anchor shown in Figs. 1 and 2 is applied to the rail base by first hooking the jaw 14 over one side of said base, as shown in dotted lines in Fig. 1, and then driving 80 said jaw snugly into engagement therewith. The angle of this jaw is normally smaller than the corresponding angle of the rail base, and as a result, said jaw is sprung when forced into position on the rail base, 85 whereby the said jaw maintains a powerful frictional grip thereon, when the anchor is in operative position. The upper side of the jaw 13 has an inclined wedging surface 15 so that when the jaw 14 is driven into 90 position, said jaw 13 may wedge past the adjacent side of the rail base and may snap upwardly into position thereon. As shown in Fig. 1, in dotted lines, the arm 11 is 95 sprung downwardly while the jaw 14 is being positioned, resulting in an upward pressure against the base of the rail by the jaw 13 at the other end of the anticreeper. The overhanging lip of the jaw 13 is sufficiently short to permit of said jaw snapping into 100 position as soon as the jaw 14 has been driven into snug engagement with the rail base, but if such upward movement is prevented, said jaw 13 may be forced up into position by means of lining bars or other tools. 105 It will be noted that the inward movement of the jaw 13, is taken up by the U-shaped portion 10, which draws the two jaws

toward each other so that the grip of the jaw 14 on the opposite side of the rail base is not relaxed.

It is obvious that the anchor maintains a firm frictional hold on the rail, regardless of the direction in which the same tends to creep by virtue of the jaw 14, and that the vertical extension at the opposite end maintains the jaw in place. The U-shaped offset 10 permits the anchor to be deformed while it is being applied and also bears against the cross tie 2 to prevent creeping of the rail in the forward direction, indicated by the arrow in Fig. 2. In practice, the projection 10 may be frozen in the ballast of the track and if the traffic is reversed, thus tending to move the rail rearwardly, the tie-abutting projection 10, will resist the creeping thrust in this direction also to some extent.

In Figs. 3 and 4, is illustrated another form of the invention wherein the end of the arm 11, instead of being provided with a jaw of the kind shown in Figs. 1 and 2, is bent upwardly and preferably slightly outwardly as shown at 16. This permits the said arm to wedge past the edge of the rail as the anchor is being positioned thereon, and permits said arm to snap upwardly 30 against the base of the rail. The end 16 may then be bent over the adjacent edge of the rail as shown in Fig. 4, by any suitable means, preferably a maul or heavy hammer, thus clamping the device around the rail base in its operative condition.

It is obvious that various changes and modifications may be made in the device as illustrated and described, and I therefore reserve the right to make such changes and modifications as fall within the scope of the appended claims.

Having thus described my invention, what I claim as new and desire to secure by Letters Patent of the United States is:—

1. A single piece rail anchor comprising a plurality of arms, a tension member intermediate said arms, a jaw at the end of one of said arms, the end of the other of said arms extending upwardly at an angle thereto and adapted to be bent over the flange of a rail after said anchor has been sprung into position.

2. A single piece rail anchor comprising a plurality of arms, one of said arms being provided with a rail base engaging jaw, the other of said arms having its end upturned and adapted to be bent around the flange of a rail after the anchor has been positioned thereon, and a downwardly projecting U-shaped member joining the inner ends of said arms and adapted to exert a horizontal

tension to retain said anchor in firm frictional engagement.

3. A rail anchor comprising a single piece of steel bent intermediate its ends to form a depending tension member and tie abutment, a rail base engaging jaw at one end and an upturned projection at the other end, said upturned projection being adapted to be bent about the flange of a rail to retain said anchor under horizontal tension.

4. A rail anchor comprising a single piece of flat steel having a rail base engaging jaw at one end, the angle of said jaw being smaller than the corresponding angle of the rail base, and means whereby said anchor snaps into position on said rail base when said jaw is driven into snug engagement therewith.

5. An anticreeper comprising a flat spring steel bar having one end bent to form a jaw which is adapted to grip one side of a rail base, and a depending U-shaped projection beneath the rail base and adjacent said jaw to transmit the creeping thrust to a tie, the other end of said bar being bent upwardly and arranged to engage the opposite side of the rail base and to maintain said jaw in effective gripping position, said upwardly bent end being adapted to be bent over the adjacent flange of the rail after said anchor has been sprung into position.

6. An anti-creeper comprising a broad flat steel bar having its ends bent to form opposed rail base engaging members, and a portion thereof intermediate said ends being bent to form a substantially U-shaped tension member adapted to depend beneath the rail base and to engage one face of a cross tie, the sides of said tension member lying in close proximity and being substantially parallel, and means whereby said tension member is sprung when said anchor is applied to a rail thereby holding the same firmly in position.

7. An anti-creeper comprising a steel bar having its ends bent to form opposed rail base engaging members, and a portion thereof intermediate said ends being bent to form a substantially U-shaped tension member adapted to depend beneath the rail base and to engage one face of a cross tie, the sides of said tension member lying in close proximity and being substantially parallel, and means whereby said tension member is sprung when said anchor is applied to a rail thereby holding the same firmly in position.

In witness whereof, I, hereunto subscribe my name this 10th day of April, A. D., 1917.

FREDERICK A. PRESTON.
